UNITED STATES PATENT OFFICE.

ADAM WEBER, OF NEW YORK, N. Y.

COKE-FURNACE.

SPECIFICATION forming part of Letters Patent No. 409,081, dated August 13, 1889.

Original application filed September 25, 1888, Serial No. 286,332. Divided and this application filed February 26, 1889. Serial No. 301,196. (No model.)

To all whom it may concern:

Be it known that I, ADAM WEBER, a citizen of the United States, and a resident of New York city, in the county of New York and State of New York, have invented certain new and useful Improvements in Coke-Furnaces, of which the following is a specification.

This invention has reference to certain improvements in the construction of coke-ovens in which the system known as the "regenerative" system or principle is carried out for heating the coking-chamber and coking the coal therein. In this invention the combustible gases generated during the coking process are utilized by conducting them through heating-flues to the combustion-chamber and burning them mingled with heated air, so as to produce a high temperature for carrying on the coking operation, thus effecting a considerable saving in the consumption of fuel by the more perfect utilization of the combustible gases given off by the coal. By my invention I also collect all the by-products of the coking-recesses.

The invention consists in the hereinafter-described improvements in the construction of the coke-oven, the coking-chamber of which is heated in the first instance by fire in a furnace under the oven. The heating thereafter is continued by the combustion of the combustible gases distilled from the coal being coked, mixed with heated air, in a combustion-chamber below the coking-chamber, said gases and air being conducted to the combustion-chamber through flues located in the side walls of the furnace and through a primary and second series of air-flues, of which the former is located below the grate of the fire-plate, while the latter is located sidewise of the uppermost gas-heating flues. The air-heating flues are heated by means of smoke-flues located between the two series of air-heating flues and connected by vertical flues in the rear wall of the oven with the mantel-flue, formed by a space between the coking-chamber and the mantel surrounding the same. The side walls of the coking-chamber and mantel are connected by dove-tailed brace-blocks and by lateral plates con-

necting the skewbacks of the coking-chamber and mantel, said plates having openings and dampers at the front and rear ends for regulating the flow of the gases at the sides and top of the mantel-flue.

In the accompanying drawings, Figure 1 represents a front elevation of my improved regenerative coke-oven, showing a range or group of ovens arranged side by side, partly in section, which is taken through the hydraulic main at the top of the ovens. Fig. 2 is a vertical transverse section of a range or group of ovens on line x x , Fig. 3. Fig. 3 represents horizontal sections of a group or battery of six ovens, each section being taken on a different plane, respectively on lines x' x' , x^2 x^2 , x^3 x^3 , x^4 x^4 , x^5 x^5 , and x^6 x^6 of Fig. 2. Figs. 4 and 5 show four vertical longitudinal sections of the ovens on four different vertical planes, respectively on the lines y' y' , y^2 y^2 , y^3 y^3 , and y^4 y^4 , Fig. 2; and Figs. 6 to 12 are detail perspective views of different shapes of flue-blocks employed in the construction of my coke-oven.

The same letters of reference indicate corresponding parts in all figures.

Referring to the drawings, A represents the coking-chamber, which forms the central part of my improved coke-oven, and which is made in the nature of a retort of blocks or tiles of fire-brick and provided with an arched dome, also formed of fire-brick blocks or tiles. It is not essential that the dome should be arched, however; it may be flat. The coking-chamber A is preferably charged from the top of the oven by a supply-channel a , formed of a fire-brick tube which is hermetically closed by a cover a' , which is formed of a ring-shaped iron frame lined with fire-brick, and it may be tightly closed by a bar and fastening-screws. The material to be coked is conveyed to the supply-channel a in cars, which move on tracks located at the top of the ovens, as shown in Figs. 4 and 5. When the coking-chamber A is charged, the channel a is closed by the cover a' , and the same is then securely fastened.

The coking-chamber A is surrounded at the sides and top by the mantel A', the top of which is arched like the top of the coking-

chamber. The corners of the coking-chamber A are supported by angle-blocks A², which are placed at some distance from each other, so as to form channels that connect the combustion-chamber B, which is located centrally below the coking-chamber, with the mantel-flue formed between the walls of the coking-chamber A and mantel A'. The side walls of the coking-chamber A are connected with the side walls of the mantel A' by dovetailed brace-blocks a³ a³, as shown clearly in Fig. 2 and in side view in Figs. 3 and 4. The combustible gases which are generated by the coking operation are conducted from the coking-chamber through a goose-neck pipe a⁴ to a hydraulic main M, which is supported on the top of the oven and connected to a suitable gas-holder. (Not shown in the drawings.) In the hydraulic main the tar, ammoniacal and other products of distillation are collected and conducted from the same to a suitable reservoir, from which they are removed for further treatment in the usual manner.

The combustion-chamber B extends to the entire depth of the oven, while the fire-place B' of the same extends to about half its length. For starting the coking operation the oven is heated with coal or coke burned in the fire-places B' until a sufficient quantity of the combustible gases has been collected from the coking-chambers of the different ovens in the gas-holder, so as to permit the continuation of the coking operation by the direct supply of said gases. These gases are conducted from the gas-holder by a gas-main G, and from the same by branch pipes G' to the lowermost flue of a series of horizontal flues D, which are arranged in the side walls of the combustion-chamber B.

The flues D are connected alternately at the rear and front, the uppermost flue D being formed of flue-blocks D' D', (shown in Fig. 10,) which are provided with lateral channels d d, that open into the upper part of the combustion-chamber and supply the combustible gases to the same. The gases are heated up in their passage through the flues D, and are mingled in the combustion-chamber with highly-heated air that is supplied through a series of air-heating flues located sidewise of the uppermost gas-heating flue D at each side of the combustion-chamber. The products of combustion pass between the blocks A² and through the mantel-flue around the side walls

of the coking-chamber, and are drawn by means of flue-openings e' in the lateral plates e, which connect the skewbacks of the coking-chamber and mantel-arch, and which are opened more or less by sliding dampers e² to ward the front and rear wall of the oven, and conducted over the arched top of the coking-chamber A to descending flues E, located in the partition-wall of the range of ovens, as shown in Fig. 5. The innermost damper can be operated by the introduction of a rod having a right-angled bend at its end, which engages with recesses in the damper or a pro-

jection therefrom, as preferred. When once adjusted or regulated, it is not necessary to again move these dampers. The vertical flues E are connected with horizontal flues E', which are arranged sidewise of the gas-heating flues D and provided at their connected front ends with sliding dampers e³. The lower flues E' communicate at their rear ends with vertical flues E² in line with the descending flues E, which terminate in an arched channel or take-off flue E³, connected with the chimney, of sufficient height to produce the required degree of draft for the proper working of the oven. The flues E' E' are located between the side walls of the combustion-chamber and the main partition-walls of the ovens and serve for the purpose of heating up the air that is drawn in for the purpose of combustion through two series of air-heating flues—a lower or primary series of flues which is located below the level of the grate of the fire-place B', while the second series of air-flues is located above the smoke-flues E' E'. The lower or primary air-heating flues F take in the air at the front of the oven and emit it through lateral channels f to the space below the grate, so as to supply heated air to the fuel on the grate for producing the more perfect combustion of the same.

The upper or second series of flues F' communicate by top channels f' in that flue nearest to the combustion-chamber with a transverse channel f² in the angle-blocks A², that support the corner-blocks of the coking-chamber. The flue-blocks, with the channels f', are shown in Figs. 6, 7, and 8. The transverse bottom channels f² of the angle-blocks A² are made with inclined sides for the purpose of facilitating the cleaning of the same by means of a scraper, which is introduced through an opening f³ in the front wall of the oven. (Indicated at the right-hand side of Fig. 4.) The heated air passes from the channels f² into the channels which lead from the combustion-chamber B to the mantel-flue surrounding the coking-chamber and mingles with the gases of combustion supplied by the eduction-channels d d of the flues D D, so as to produce the perfect combustion of all the gases and keep the outer surface of the coking-chamber enveloped by a sheet of flame, so as to subject the coal in the coking-chamber to a high temperature and convert it quickly into coke.

In place of arranging the eduction-channels for the heated air at the top of the innermost air-flue F' and in the angle-blocks A², they can be arranged in lateral flue-blocks F², located above the uppermost gas-heating flue D, as shown in Fig. 12. By using the flue-blocks F² the combustion of the gases takes place in the combustion-chamber directly below the central part of the retort. With either arrangement of the eduction-channels the material in the coking-chamber is subjected to a high temperature by the combustion of the heated gases and the heated air supplied to

and mingled with the same. The former arrangement is to be preferred when the highest temperature is desired to be supplied to the side walls of the coking-chamber, while the latter is preferred when the highest temperature is to be applied to the bottom of the coking-chamber.

When the combustible gases are supplied, the fire in the fire-place may be discontinued and the lower series of air-flues closed. When the coking operation is completed, the coke is removed from the coking-chamber through an opening in the front wall of the oven, which opening is closed like the front openings of the fire-place and ash-pit by tightly closing iron doors lined with fire-bricks, which doors are closed by means of bars and clamping-screws, as customary in coke-ovens and gas-benches.

20 The operation of the furnace is as follows: The retorts are charged with the required quantity of coal, coal-dust, or other material to be coked and the fire then started in the fire-place, so as to start the coking process.

25 The gases generated in the coking-chamber are conducted through the hydraulic main to the gas-holder, and, after the separation of the by-product, from the same to the gas-main, connecting-pipes, and gas-heating

30 flues located in the side walls of the combustion-chamber into the latter. They are mingled in the combustion-chamber with the heated air supplied by the education-channels of the upper series of air-heating flues. As soon as the ovens can be supplied with the gases obtained from the distillation of the coal in the coking-chamber the fire in the fire-place may be discontinued. The products of combustion are conducted through

40 the mantel-flues and descending rear smoke-flues to the horizontal smoke-flues between the lower and upper series of air-heating flues, and from the same through shorter descending flues to the take-off flue and the

45 chimney.

The smoke-flues serve for heating the rear walls of the coking-chamber, as well as for heating the air-flues and the gas-flues located in the side walls of the combustion-chamber, so that the regenerative principle on which my improved coke-oven is based is well carried out.

Because of the peculiar construction of the furnace above described and hereinafter

claimed I secure not only great strength in the structure to withstand the strains resulting from the weight of coal, &c., expansible gases, contraction and expansion, &c., but also by the employment of the tiles and angle-blocks, the dovetail blocks, &c., I am enabled to erect the furnaces at much less cost and much more speedily than when they are not employed.

I do not herein claim certain features of my invention which are herein described and shown. I do not, however, abandon the same, they being set forth and claimed in another application for Letters Patent filed by me on the 25th day of September, 1888, now pending as Serial No. 286,332, of which case this present case is a division under the ruling of the Commissioner of Patents made in said Case No. 286,332.

Having thus described my invention, I claim as new and desire to secure by Letters Patent—

1. The combination of a coking-chamber formed of blocks or tiles, a mantel surrounding said coking-chamber and forming a mantel-flue around the same, dovetailed lateral braces connecting the side walls of the coking-chamber and mantel, and a combustion-chamber below the coking-chamber, substantially as set forth.

2. The combination of a coking-chamber formed of blocks or tiles, a mantel surrounding said coking-chamber, angle-blocks supporting the bottom of the chamber, and dovetailed brace-blocks connecting the side walls of the coking-chamber and mantel, and a combustion-chamber below the coking-chamber, substantially as set forth.

3. The combination of a coking-chamber formed of blocks or tiles, a mantel surrounding the coking-chamber, lateral brace-blocks connecting the side walls of the coking-chamber and mantel, and lateral plates connecting the upper corners of the coking-chamber and mantel, said plates being provided with front and rear openings, and sliding dampers for regulating the size of said openings, substantially as set forth.

Signed at New York, in the county of New York and State of New York, this 11th day of February, A. D. 1889.

ADAM WEBER.

Witnesses:

PHILLIPS ABBOTT,
MORRIS ARNHEIM.
